UNITED STATES PATENT OFFICE

JOSEPH O'NEILL, OF AKRON, OHIO

ADVERTISING DISPLAY DEVICE

Application filed December 6, 1929. Serial No. 412,065.

This invention relates to advertising display devices such as illuminated representations or simulations of goods being advertised.

5 The general purpose of the invention is to provide an improved inexpensive advertising display device of the above character, said device being capable of exposure to atmospheric conditions without deterioration.

10 Heretofore devices of this sort have been made of glass or the like which are comparatively expensive and easily broken, or of translucent paper or parchment material which, while cheap, are not capable of withstanding atmospheric conditions and are not easily manipulated to form them into the desired shapes.

15 The present invention has for its objects the provision of an illuminated display device including an interior frame of a shape determined by the shape of the article to be simulated in which electric lights may be supported and over which is applied a covering of a translucent, semi-stiff, flexible material 20 adapted to take a "set" in any shape to which it is formed. This material comprises wire screen such as ordinary window screen embedded in a layer of a flexible, waterproof composition comprising a derivative of cellulose, this material being obtainable on the market under the trade name of "cello-glass."

25 The foregoing and other objects of the invention are attained in the advertising display device shown in the accompanying drawings and described below. It is to be understood that the invention is not limited to the particular form thereof shown and described.

30 Of the accompanying drawings,

Figure 1 is an elevation of a display device embodying the invention;

Figure 2 is a vertical diametral section through said device;

35 Figure 3 is a top plan thereof;

Figure 4 is a plan of a portion of the covering material; and

Figure 5 is a section through the covering material as along line 5-5 of Figure 2.

40 Referring to the drawings, the numeral 10

designates a suitable frame which in the particular form of the invention shown is shaped like an inverted isosceles triangle having an annulus 10^a secured to the top thereof so as to be adapted for a display simulating an ice cream cone. One or more sheets of the material described above and comprising wire screen 11 embedded in a translucent cellulose derivative 12 are shaped to cone 55 shape about said frame as at 13, edges of the sheet being overlapped at one or more places 60 as at 14 over the frame and the covering being secured to the frame as by rivets 15, 15.

To simulate ice cream in the cone, a cap 16 65 is formed of, or shaped from, one or more pieces of the sheet material 11, 12 and this cap may be removably bolted onto the top of the cone by bolts extending through the annulus 10^a whereby the cap can be removed 70 for access into the device.

Electric lamp bulbs 17, 18 and 19 may be mounted at suitable points in frame 10, the lamp 17 to illuminate the cap 16 and the lamps 18 and 19 to illuminate the body of 75 the cone. Leads 20 are extended into the body of the cone through a plug 21 fixed in the bottom thereof for connecting the lamps to a source of electricity.

The display device thus provided may be 80 mounted on a suitable bracket for placement at any desired location. A bracket standard 22 is shown in the drawings provided with members 22^a so arranged as to define a cone-shaped receptacle in the standard for the cone display device shown.

85 The body of the cone may be colored and lined as indicated to simulate the coloring and formation of an ice cream cone and the cap may be colored to simulate ice cream. This can be accomplished by use of coloring 90 in the covering material when made or by decorating the material either before or after applying it to the frame.

95 It will be apparent that any desired shapes can be imparted to the material to apply it to frames of various shapes, the wire in the material "setting" the material in any shape to which it is formed either by use of molds or by hand manipulation thereof.

100 Modifications of the invention may be re-

sorted to without departing from the spirit thereof or the scope of the appended claims.

What is claimed is:—

1. An advertising display device comprising a frame shaped as an inverted isosceles triangle with an annulus at the top thereof, one or more electric lamps mounted in said frame, a covering for said frame comprising one or more sheets of translucent cellulose material having wire fabric embedded therein wrapped about and secured to the frame to provide a cone-shaped body, a cap comprising said sheet material shaped to simulate a mass of ice cream in said cone, said cap being removably mounted on the annulus of said frame, said body and cap material being colored to simulate a cone containing ice cream, and leads extending through the bottom of the cone for supplying electricity to said lamps.
2. An advertising display device comprising a frame shaped as an inverted isosceles triangle with an annulus at the top thereof, one or more sources of lights mounted in said frame, a covering for said frame comprising one or more sheets of translucent cellulose material having wire fabric embedded therein wrapped about and secured to the frame to provide a cone-shaped body, and a cap comprising said sheet material shaped to simulate a mass of ice cream in said cone, said cap being removably mounted on the annulus of said frame, said body and cap material being colored to simulate a cone containing ice cream.
3. An advertising display device for simulating an article to be advertised, said device comprising a frame of suitable shape, one or more light sources in the frame, and a covering of translucent cellulose sheet material having wire fabric embedded therein applied to the frame, said material being shaped and colored to simulate said article.
4. An advertising display device for simulating an article to be advertised, said device comprising a frame of suitable shape, and a covering of translucent cellulose sheet material having wire fabric embedded therein applied to the frame, said material being shaped and colored to simulate said article.

JOSEPH O'NEILL.
